UNITED STATES PATENT OFFICE.

LAWRENCE R. GOLLADAY, OF WILKINSBURG, PENNSYLVANIA, ASSIGNOR TO WESTINGHOUSE ELECTRIC & MANUFACTURING COMPANY, A CORPORATION OF PENNSYLVANIA.

RESISTOR FOR LIGHTNING ARRESTERS.

Application filed May 10, 1922. Serial No. 559,917.

To all whom it may concern:

Be it known that I, LAWRENCE R. GOLLADAY, a citizen of the United States, and a resident of Wilkinsburg, in the county of Allegheny and State of Pennsylvania, have invented a new and useful Improvement in Resistors for Lightning Arresters, of which the following is a specification.

My invention relates to protective devices, more especially to a device for protecting electrical apparatus, such as transformers, in high-voltage transmission lines.

It is among the objects of this invention to provide a protective device which shall function to absorb abnormal static charges accumulating on the line, which shall extinguish the arc resulting from the current flowing as the result of such discharges and which shall have a heat-absorbing capacity to prevent damage to, and avoid the necessity of renewal of, parts of the apparatus.

It is a further object of this invention to provide a device of this general character which shall be of simple, inexpensive construction and which shall require no special attention during its service life.

Various forms of protective devices embodying the well known horn gaps in combination with resistors have been employed to advantage. My present invention is designed to provide a structure embodying horn gaps having a series and shunt resistance in the form of an electrolyte in combination therewith.

Such a structure has the advantage of providing a large heat-absorbing capacity and greater discharge capacity with the certainty of extinguishing the arcs formed between the horn gaps.

In the accompanying drawings constituting a part hereof and in which like reference characters designate like parts,

Figure 1 is a vertical cross-sectional view of a protective device embodying the principles of my invention;

Fig. 2 is a cross-sectional view thereof taken along the line II—II of Fig. 1; and

Fig. 3 is a diagrammatic view showing the electrical connections of the device.

The device illustrated in Figure 1 comprises a plurality of horn-shaped electrodes 1, 2 and 3 secured to a porcelain base 4 hav-

ing a plurality of annular projections 5 and 6 depending downwardly therefrom. The base is supported by a cylindrical metal container 7 which is provided with a ground connection 8.

Electrodes 1, 2 and 3 are so arranged as to provide a plurality of gaps 9 and 10 therebetween and the central electrode 2 is provided with a terminal 11 which is disposed within the cylindrical column formed by the annulus 6. An annular terminal 12 is secured to the electrode 3 and rests on a flange 13 projecting inwardly on the member 5. The container 7 is filled with a suitable electrolyte 14 to establish a circuit between the electrode terminals 11 and 12 and the casing 7. The electrolyte 14 establishes a cylindrical resistance column in series with the terminal 11 and the ground connection 8 and an annular column from the terminal 12 to ground, as is illustrated in the diagrammatic view, Fig. 3, in which the resistance 15 represents the column 6 and the resistance 16 the annular column 5.

The device operates as follows: the electrode 1 connected to a line circuit, such as a power-transmission line, and the gap 9 is of such size as will withstand ordinary or normal potentials in the circuit, but, with an unusual static disturbance, such as is caused by lightning, the dielectric capacity of the air gap 9 will break down and the current following the discharge will establish an arc between the electrodes 1 and 2 which will be extinguished by rising between the divergent horns and by the series resistance of the liquid column making contact with the terminal 11 and the ground circuit 8. The current will be limited by the resistor within the ability of the horns to extinguish. However, if the abnormal potential is not relieved, but continues to rise, the potential between the electrodes 2 and 3 will rise until the dielectric capacity of the air gap 10 fails, causing an arc to be established thereacross which will be extinguished by the divergent horns 3 and 2 or by the resistance of the annular liquid column contained within the annular depending member 5 which is shunted across the gap 10 and provides a path from the terminal 12 to ground through the casing 7. This double

series and shunt connection provides a greater discharge capacity and the liquid resistors provide a large heat-absorbing capacity with a certainty of extinguishing the 5 arc.

The combined action of the horns and resistors protects the apparatus in the circuit as the combination is designed to function when the maximum voltage for 10 which the system is designed is reached. The electrolytic resistors are not essentially of proportional capacity with the dielectric strength of the air gaps, but the series and shunt resistors impart such characteristics 15 to the device as to make it capable of withstanding exceedingly great discharge without injury.

Although I have described a specific embodiment of my invention, it will be obvious to those skilled in the art that various modifications may be made in the details of construction thereof without departing from the principles herein set forth. For instance, the porcelain base or the metal 25 housing may be of any suitable shape or contour to establish the shunt and series resistance and for mounting the horn gap electrodes. Any electrolyte of a suitable specific resistance may be employed to establish the resistors between the electrode 30 terminals and ground. The discharge gaps may be of different dielectric strength by varying the spacing of the horns. The columns of liquid need not necessarily be concentric but may be placed in any position 35 relative to each other.

I claim as my invention:

1. The combination with a liquid resistance, of a plurality of discharge gaps, said 40 resistance being electrically connected between said gaps and ground.

2. The combination with a liquid resistance, of a plurality of discharge gaps, said liquid resistance being connected in series 45 between said gaps and ground.

3. The combination with a liquid resistance, of a plurality of discharge gaps, said

liquid resistance being shunted across said gaps and connected to ground.

4. The combination with a liquid resistance, of a plurality of discharge gaps, said liquid resistance being shunted across some 50 of said gaps and connected to ground.

5. The combination with a liquid resistance, of a plurality of discharge gaps, said 55 liquid resistance being series and shunt connected between said gaps and ground.

6. The combination with a liquid resistance, of a plurality of discharge gaps, said liquid resistance being connected in series 60 between one of said gaps and shunted across another of said gaps and connected to ground.

7. The combination with a liquid resistance, of electrodes, a ground container, an 65 electrolyte and a plurality of annular insulating spacers therein, and a plurality of discharge gaps connected to said electrodes extending into the spaced portions of said electrolyte to provide a series and shunt 70 connection between said gaps and ground.

8. The combination with a liquid resistance, of electrodes, a grounded container, an electrolyte and a plurality of annular insulating spacers therein, and a plurality 75 of discharge gaps connected to said electrodes and extending into the spaced portion of said electrolyte to provide a series connection between one of said gaps and ground, and a shunt connection across another gap and ground. 80

9. The combination with a liquid resistance, of electrodes, a grounded metal container, an electrolyte and a plurality of annular porcelain spacers therein, and a 85 plurality of horn gaps connected to said electrodes and extending into the spaced portions of said electrolyte to provide a series and a shunt connection between said gaps and ground. 90

In testimony whereof, I have hereunto subscribed my name this 2nd day of May, 1922.

LAWRENCE R. GOLLADAY.
